TIRE RIM

Charles E. Grawey, Peoria, Keith E. Koch, Tremont, and
Robert W. Untz, Hanna City, Ill., assignors to Cater-
pillar Tractor Co., Peoria, Ill.

Filed Dec. 27, 1971, Ser. No. 212,881

Term of patent 14 years

Int. Cl. D12—16

U.S. Cl. D14—30 R

FIG. 1.

FIG. 2.

FIG. 3.

FIG. 4.

FIG. 5.

FIG. 1 is a perspective of the tire rim embodying our new design;

FIG. 2 is a perspective of the tire rim shown in FIG. 1 with parts broken away to show additional detail;

FIG. 3 is an edge view of the tire rim shown in FIG. 1;

FIG. 4 is a front elevation of the tire rim shown in FIG. 1; and

FIG. 5 is a rear elevation of the tire rim shown in FIG. 1.

We claim:

The ornamental design for a tire rim, substantially as shown and described.
